UNITED STATES PATENT OFFICE.

FRED WEGNER AND JOHN PETERS, OF FAIRPORT, NEW YORK, ASSIGNORS TO SANITARY CAN COMPANY, OF FAIRPORT, NEW YORK, A CORPORATION OF NEW YORK.

AUTOMATIC FEED DEVICE FOR CAN-HEADS OR OTHER ARTICLES.

1,013,344.

Specification of Letters Patent.

Patented Jan. 2, 1912.

Application filed May 24, 1910. Serial No. 563,183.

To all whom it may concern:

Be it known that we, FRED WEGNER and JOHN PETERS, citizens of the United States, residing at Fairport, in the county of Monroe and State of New York, have invented a new and useful Improvement in Automatic Feed Devices for Can-Heads or other Articles, of which the following is a specification.

10 Our invention relates to improvements in mechanism or devices for feeding can heads or caps to machines for performing operations thereon.

The object of our invention is to provide 15 a can head feed mechanism of a simple, efficient and durable construction, by means of which the top or bottom heads of cans, can caps or other disks may be accurately, rapidly and with certainty and reliability 20 fed from a pile or stack one by one to the devices for performing operations thereon, such, for example, as a coating mechanism for coating the flanges of the heads or caps, a seaming mechanism for seaming the heads 25 to a can body, a can heading machine or other machine.

Our invention consists in the novel construction of parts and devices and in the 30 novel combinations of parts and devices herein shown and described and more particularly specified in the claims.

In the accompanying drawing forming a part of this specification, Figure 1 is a plan view of a feeding device embodying our 35 invention, the same being, for convenience, illustrated in connection with a mechanism for applying a cement or packing composition to the flange of the can head and to which the can heads are fed by our improved can head feeder. Fig. 2 is a central, vertical section on line 2—2 of Fig. 1. Fig. 3 is a horizontal section on the broken line 3—3 of Fig. 2 and Fig. 4 is a cross section on line 4—4 of Fig. 2.

40 In the drawing, 1 represents the frame of the mechanism for feeding the can heads, 2 represents the driving shaft of a machine for performing some operation upon the can head which is to be fed, and 3 is a can support belonging to said machine and to 45 which support the head is to be fed by my improved feed mechanism.

A pile or stack 4 of can heads 5 placed one flat on top of another are contained within an open bottom can head holder 6, 55 preferably comprising a base ring furnished with three or more upright guide rods 7 for convenience of placing can heads in the holder. The pile or stack of can heads in the holder 6 rest or are normally supported upon reciprocating can head separators 8, preferably two in number, and oppositely disposed so as to be engaged by a short segment of the lowermost can head of the pile or stack. The separators 8 are 60 each furnished with a bevel face 9 at one end to adapt them to readily enter between the can heads in the pile or stack and separate the lowermost one from those above. The separators 8 are adapted to be reciprocated in suitable guides 10 on the frame of the machine. The feed slide 11 by which the can heads are pushed or fed one by one from the holder 6 along the stationary feed plate or table 12 to the rotary chuck or can 65 support 3 upon which they are to be delivered, reciprocates in suitable guides 13 on the frame of the machine and is preferably furnished with a V shaped crotch or notch 70 for centering the can heads as they are 75 pushed forward by the feed slide. The feed slide 11 is provided with a pair of yielding can supports or fingers 15 resting upon light springs 16 interposed between the fingers 15 and the feed slide 11. The pins 17 cause 80 the fingers or yielding supports 15 to be moved with the feed slide while permitting the same to yield freely up and down. The fingers or yielding supports 15 are preferably furnished with beveled front ends 18 85 to facilitate the dropping of the lowermost can head down upon the table 12 in the notch 14 of the feed slide when the lowermost can head has been released by the separators 8. The separators 8 are given the 90 necessary reciprocating movement to cause them to alternately support the pile of can heads in the holder 6 and to permit the same to be alternately supported by the spring fingers or supports 15 of the can head feed 95 slide, and to cause them on their return movement to separate the lowermost can head from the stack or pile, preferably by means of a slide 19, the cross bar 20 of 100

which is connected by a lever 21 and slotted link 22 with the feed slide 11 by a pin 23, which fits in a long slot 24 of the link 22. The feed slide 11 may be reciprocated by 5 any suitable connecting mechanism, such, for example, as a connecting link and lever, not shown, from the driving shaft 2, or other moving part of the machine, to the chuck or can support 3 of which the can 10 heads are to be fed.

In operation, when the feed slide 11 is retracted, as shown in the figures of the drawing, the can heads in the holder 6 rest upon the separators 8 when the feed slide 11 makes 15 its forward stroke to push the can heads upon the feed table 12 onto the support 3. The reciprocating separators 8 are pushed forward at the final portion of the stroke of the feed slide 11, thus causing the pile of can 20 heads in the holder 6 to drop down upon the spring fingers or supports 15 of the feed slide which now supports the can heads in the holder. And when the feed slide 11 makes its return stroke at the final portion 25 thereof, the beveled end edges of the separators 8 enter between the lowermost can head and those above it in the holder, thus separating the lowermost can head from the pile or stack, the spring fingers or yielding 30 supports 15 yielding sufficiently to permit the separators 8 to thus enter between the can heads, thereby separating the lowermost can head from those above it and permitting it to drop down upon the feed table 12 in position to be pushed forward by the next forward stroke of the feed slide. The fingers 15 being yielding or spring supported, enables 35 the separators 8 to readily enter between the lowermost can head and those above it, and 40 renders it unnecessary for the separators to raise the entire pile or stack of can heads which might interfere with the rapid operation of the machine, especially if the can heads should tend to bind in the holder while 45 the separators are entering between the can heads to force the can heads upward. The lever 21 is connected to the cross bar 20 of the slide 19 by a pin 25 which passes through a slot 26 in the lever. The feed slide 11 is 50 furnished with an ejector finger 27 for pushing the can head from the rotary chuck or support 3 after it has been operated upon by the mechanism to which the can head is fed. The ejector finger 27 has a spring 28 which 55 yieldingly holds it in position so that it may swing out of the way and thus pass the can head on the support 3 when the feed slide makes its return movement.

We claim:—

60 1. In a feed device for feeding can heads or other articles one by one from a pile or stack, the combination with a holder for the articles to be fed, of a reciprocating feed slide and reciprocating separators, said feed 65 slide and separators moving in the same di-

rection alternately supporting the pile of articles in the holder, substantially as specified.

2. In a feed device for feeding can heads or other articles one by one from a pile or 70 stack, the combination with a holder for the articles to be fed, of a reciprocating feed slide and reciprocating separators, said feed slide and separators alternately supporting the pile of articles in the holder, said feed 75 slide having yielding supporting fingers for engagement with the can heads, substantially as specified.

3. In a feed mechanism for can heads or other articles, the combination with a holder 80 for containing the articles to be fed in a pile or stack, of a reciprocating feed slide having spring supported fingers and movable separators, said separators and fingers moving in the same direction alternately supporting 85 the stack or pile of articles in the holder and connecting means between said separator and said feed slide for actuating the separators from the feed slide, substantially as specified. 90

4. In a feed mechanism for can heads or other articles, the combination with a holder for containing the articles to be fed in a pile or stack, of a reciprocating feed slide having 95 spring supported fingers and movable separators, said separators and fingers alternately supporting the stack or pile of articles in the holder and connecting means between said separator and said feed slide for actuating the separators from the feed slide, 100 said connecting mechanism comprising a lever and a slotted link, substantially as specified.

5. In a feed device for feeding can heads or other articles one by one from a pile or 105 stack, the combination with a holder for the articles to be fed, of a reciprocating feed slide and reciprocating separators, said feed 110 slide and separators moving in the same direction alternately supporting the pile of articles in the holder, said separators having beveled ends to facilitate their entrance between the can heads, substantially as specified.

6. In a feed device for feeding can heads 115 or other articles one by one from a pile or stack, the combination with a holder for the articles to be fed, of a reciprocating feed slide and reciprocating separators, said feed 120 slide and separators moving in the same direction and alternately supporting the pile of articles in the holder, said slide being provided with a pivotally mounted spring controlled finger on its forward end, substantially as specified. 125

7. In a feed device for feeding can heads or other articles one by one to a station where the can head is adapted to be operated upon, the combination with a holder for the articles to be fed, of a reciprocating feed 130

slide, said slide having means thereon for cutting out the lowermost can head in the holder upon a complete reciprocation, said slide having also thereon at its forward end 5 a yieldingly mounted finger adapted to engage and eject a can head fed by the slide on a preceding movement, from the operating station, in advance of the can head being fed

to the operating station, substantially as specified.
